UNITED STATES PATENT OFFICE.

JOHN B. KELLY, OF CHICAGO, ILLINOIS.

CARBURETER.

984,276.

Specification of Letters Patent. Patented Feb. 14, 1911.

Application filed March 21, 1910. Serial No. 550,737.

To all whom it may concern:

Be it known that I, JOHN B. KELLY, a citizen of the United States, residing at Chicago, in the county of Cook and State of Illinois, have invented a new and useful Improvement in Carbureters, of which the following is a specification.

My primary object is to provide new and improved means for controlling the admission of air, for mixture with the fuel-oil, into the mixing chamber, whereby the proper amount of air may be supplied regardless of the speed at which the engine supplied therefrom operates.

15 The accompanying drawing shows by a view in sectional elevation a carbureter constructed in accordance with my invention.

The mixing chamber of the carbureter is illustrated at 7 and is formed with an outlet 20 8 controlled by a throttle-valve 8, and communicates with an air-conducting passage 9 below it. The passage 9 contains an upwardly opening nozzle 10 which communicates through the passage 11 with the usual 25 valve-equipped gasoline supply chamber (not shown).

Screwed into an opening 29 in the wall of the chamber 7 directly above the passage 9 is a plug 30 containing an opening 31 with 30 the wall of which a needle-valve 32 has screw-threaded connection for the purpose of permitting the valve to be adjusted up and down. The lower end of this valve which is of inverted conical form, as represented at 33, is arranged concentric with relation to the outlet 34 of the nozzle 10, the wall of which is of inverted frusto-conical shape as represented at 35.

35 The passage 9 opens into a combined 40 priming cup and air-inlet device 36 which, in its preferred embodiment, is formed of a cup-shaped member 37 screwed into the circular wall 38 forming the passage 9 and containing a plurality of radially-disposed 45 openings 39 reaching short of the bottom of the cup.

Screwed into one end of the wall 40 forming the mixing chamber 7 is a plug 41 50 formed with a relatively large circular opening 42 having its inner edge beveled as indicated at 43. The outer end of this plug is of spider-frame construction as represented at 44, the central hub-portion 45 of which contains an opening 46 of angle-shape in 55 cross-section in which a valve-stem 47 is reciprocably supported. The inner end of

the stem 47 carries a circular valve-disk 48 having a beveled edge-portion 49 at which it is adapted to seat against the beveled portion 43 of the plug 41. The opposite end of the stem 47 which is reduced in diameter and is threaded externally as represented at 50, is surrounded by an internally screw-threaded sleeve 51 screwed upon the threads 50 and adjustable thereon for a purpose hereinafter explained, the outer end of the stem 47 carrying a nut 52 adapted to hold the sleeve 51 on the stem 47 in adjusted position. The sleeve 51 is also externally threaded as represented, and screwing upon these threads is a nut 53 of preferably hexagonal form, this nut having one face recessed as represented at 54 for receiving one end of a coiled spring 55, this spring being confined between the nut 53 and a dust-cap 56 surrounding a shouldered portion 57 of the plug 41. A nut-lock 58 secured to the stem 47 between the sleeve 51 and the nut 52, co-operates at its free flexible end-portion 59 with the nut 53 for holding the latter in 80 adjusted position on the sleeve 51.

In the operation of the engine equipped with the carbureter, the oil is drawn, by the engine suction, from the supply thereof through the nozzle 10 into the mixing-chamber 7 where it is mixed with the air supplied through the openings in the priming cup, it being understood that the latter is adjusted in the wall 38 to cause it to permit the requisite amount of air to enter the passage 9 for 90 operating the engine at low speed. The valve 48 is an auxiliary air-valve for supplying air, under the suction action of the engine, to the mixing-chamber 7, in addition to that supplied through the cup, or main air-inlet 36, when the engine is operating at intermediate and high speeds. It is preferred that the valve 48 be first adjusted to regulate the air supplied through it for running the engine at high speed, this being 100 done by screwing the sleeve 51 on the stem 47 to a position in which the inner end of this sleeve is spaced from the hub 57 a distance equal to the displacement of the disk from the seat 49 necessary for admitting to 105 the chamber 7 the proper volume of air for running the engine at high speed. After this adjustment has been made, the nut 53 should be adjusted on the sleeve 51, while the engine is running at intermediate speed, 110 to so tension the spring 55 as to cause the proper amount of air to enter the chamber

for running the engine at speeds intermediate high and low speeds.

By forming the auxiliary air-inlet valve as described, it is rendered, by reason of the spring feature, sufficiently sensitive to cause it to operate when the engine is running at speeds intermediate the low and high speeds, to supply to the carbureter the requisite amount of air, and operates automatically, without interfering with or affecting its sensitiveness for operation at intermediate speeds, to limit the opening of the valve for controlling the air admitted to the carbureter for operating the engine at high speed.

What I claim as new, and desire to secure by Letters Patent, is—

1. In a carbureter, the combination with a mixing chamber, and means for supplying oil to said chamber, of means for supplying air to said chamber comprising a valve, a stop-device adjustable on the stem of said valve operating to limit the opening of the latter, a spring surrounding the valve-stem for yieldingly holding the valve to its seat, and means for adjusting the tension of the spring, for the purpose set forth.

2. In a carbureter, the combination with a mixing-chamber, and means for supplying oil to said chamber, of means for supplying air thereto comprising a valve, a sleeve threaded on the stem of said valve operating to limit the opening of the valve, a nut screwing upon the sleeve, and a coiled spring surrounding the valve-stem and coöperating

with said nut for yieldingly holding the valve to its seat.

3. In a carbureter, the combination with a mixing-chamber, and means for supplying oil to said chamber, of means for supplying air to the chamber comprising a stationary member formed with a valve-seat through which said chamber communicates with the atmosphere, a reciprocable stem carrying a member adapted to bear against said seat to close the valve, a stop-device adjustable on said stem and operating in conjunction with said stationary member to limit the movement of said stem, a spring operating to yieldingly hold the valve closed, and means for adjusting the tension of said spring independently of said stop-device, for the purpose set forth.

4. In a carbureter, the combination with a mixing-chamber, and means for supplying oil to said chamber, of means for supplying air to said chamber comprising a valve, an adjustable stop-device for limiting the opening of said valve, and a spring coöperating with said valve for holding it yieldingly against its seat, and adjustable independently of said stop-device, and without varying the adjustment of the latter, for the purpose set forth.

JOHN B. KELLY.

In presence of—

R. A. SCHAEFER,
JOHN WILSON.
